INFLATABLE PLAYING BALL
CONSTRUCTION

Hugo Goldsmith, Cincinnati, Ohio, assignor to
The P. Goldsmith Sons Company, Cincinnati,
Ohio, a corporation of Ohio

Application February 19, 1937, Serial No. 126,687

5 Claims. (Cl. 273—65)

My invention relates to inflatable playing balls and to the valve and bladder assembly associated with the outer cover of the playing ball.

It is the object of my invention to provide an inflatable playing ball construction in which panels form the outer cover of the ball in which an inflatable resilient bladder composed of material such as rubber is so mounted within the cover that the bladder may be inflated through a small hole in one of the panels of the cover, the mounting cover construction and arrangement being such that the opening in the cover is sealed against leakage into the space between the cover and bladder, and in which the valve itself is leak-proof.

Another object of my invention is to provide an inflatable bladder and a leak-proof valve therefor which may be assembled either with the ball having panels uniformly stitched throughout, and which accordingly may be called a laceless ball, or for use in connection with balls, the stitch line between panels of which is provided with an inflating opening.

A further object is the provision of a playing ball construction which may also be used in combination with a cover formed by stitched segments of fabric on the outer surface of which panels of leather or the like may be secured by cementing.

It is a further object of my invention to provide an inflatable bladder and valve assembly which will be available for use with a playing ball, the cover of which is so composed as to present a smooth contoured surface throughout, and which may therefore be called not only laceless but stitchless.

In combination with the panel of a laceless ball it is an object of my invention to provide an inflatable bladder so mounted with relation to a small aperture in one of the panels that there is no deflection from the even contour of the outer cover of the ball because of the valve assembly and mounting.

It is a further object of my invention to provide a valve having additional safe guards to prevent leakage either through the valve opening or around the mounting for the valve.

The above objects and other specific objects to which reference will be made in the ensuing disclosure, I accomplish by that combination and arrangement of parts of which I have illustrated a preferred modification.

Referring to the drawing:

Figure 1 represents a sectional view of the improved valve.

Fig. 2 is a sectional view of a portion of a playing ball showing one preferred method of mounting the valve and bladder within the cover.

Fig. 3 is a sectional view showing a modified type of valve and bladder mounting in a different type of playing ball.

Like reference characters are employed to indicate like parts in the several figures of the drawing. In Fig. 1, the valve has a solid stem *a*, provided with a thin flange *b*, and a projecting nipple *c*. Extending from the nipple *c* there is a slit *e*, preferably formed by a thin, very sharp knife which extends down through the stem to a position where it intersects a transverse slit *f*, close to the innermost end of the valve stem.

Surrounding the stem *a* are the resilient constricting bands *g* and *h*. The band *g* serves to compress the valve stem to prevent leakage through the slit *e* and the band *h* serves to provide additional constricting means to prevent leakage. It will be noted that the band *h* is slightly longer than the band *g* so that the lower end of the outer resilient band extends down over the lower edge of the inner band *g*, thereby sealing the inner band *g* from any contact with air, thus preventing oxidization and deterioration of the rubber.

The flap at the inner end of the valve stem yields downwardly to the position indicated in dotted lines at *f'* when an inflating tool is inserted down through the slit *e*, guided thereto by the passage in the nipple.

Referring now to the mounting of the valve on the bladder and the mounting of the bladder within the cover, an opening *j* is provided in the bladder in which the stem of the valve is inserted or vulcanized in place. Adhesive as indicated at *k* is applied to the under surface of the flange *b* and the wall of the bladder is thereby secured thereto.

In Fig. 2, the cover panels of the playing ball are indicated at *l*. Permanent stitching as shown at *m* secures the panels of the cover together in a substantially leak-proof manner, the application of water-proofing material to the stitched seams rendering the cover substantially waterproof. An aperture *n* in the cover seats the nipple *c* of the valve and adhesive as indicated at *o*, is applied which permanently seals the upper surface of the flange to the inside of the cover with the nipple *c*, lying within and not substantially projecting beyond the opening *n*. The nipple thus serves for properly locating the bladder, and guiding the valve stem, and the flange on the valve cements the bladder and ball cover together.

The cementing of the valve flange to the cover and the cementing of the valve flange to the bladder makes a substantially leak-proof joint.

In Fig. 3, the cover panels may be cemented in position on an inner fabric ball *p*. The lining may be of fabric panels permanently and uniformly stitched throughout with the outer cover panels cemented in position without stitching. The lining is, like the leather cover, susceptible to adhesive. In this type of playing ball I may provide an additional reinforcement which consists in the flexible disc *q* which is of greater extent than the flange *b*. Preferably made of rough surfaced leather, adhesive as indicated at *r* is provided on the upper surface of the flange *q*, and adhesive as indicated at *s* is provided on the under surface, so that whereas the attachment of the valve flange to the cover where the ball is unlined is adequate where the diameter of the disc *q* is, for example, one and one-half inches, when a fabric inner ball is used covered with leather panels, the attachment is provided by a disc, for example, three inches in diameter. It will be observed that in the construction shown in both Figs. 2 and 3, the contour of the panel of the cover is in no way disturbed by the attachment of the valve flange thereto. This promotes accurate bouncing of the playing ball and avoids the formation of a non-resilient dead spot where the attachment of the valve, bladder and cover occurs.

The valve and bladder assembly in some types of balls constitutes the entire ball, the cover being formed by the outer wall of the bladder which is either coated with fabric material or the bladder is so dimensioned as to thickness and so treated that the outer cover of the bladder forms the outer cover of the ball. The valve and bladder assembly may also be employed with other inflatable articles.

I have shown my invention in combination with a playing ball of the laceless type, but it will be understood that the same construction may be used in combination with a laced ball, with a ball having an inflating opening in the seam and with

a so-called stitchless ball in which the outer cover is formed of segments of leather cemented in position.

Having thus described my invention, what I claim as new and desire to secure by Letters Patent is:—

1. A valve for an inflatable article having a wall with an opening through which a stem of said valve extends said stem having a flange secured to said wall, said stem having a slit extending lengthwise therethrough for inflating said article, a resilient band surrounding said stem for sealing said slit and means covering said resilient band and additionally constricting said band for preventing deterioration of the resiliency of said band.

2. A valve for an inflatable article having a wall with an opening through which a stem of said valve extends said stem having a flange secured to said wall, said stem having a slit extending lengthwise therethrough for inflating said article, a resilient band surrounding said stem for sealing said slit and means covering said resilient band for preventing deterioration of the resiliency of said band, said means comprising a relatively wider resilient band covering both ends of said first noted band.

3. A valve for an inflatable ball comprising a stem having a slit extending through said stem and a resilient band surrounding said stem with resilient means surrounding and enclosing said band for the purposes described.

4. A valve for an inflatable ball comprising a slotted stem with a tensioned band compressing said stem to prevent leakage through said slit, and means enclosing said band and constricting it for preventing oxidation and deterioration of said band.

5. A valve for an inflatable ball comprising a stem having a slit extending therethrough, a rubber band of a given width surrounding said stem and a second wider band surrounding and enclosing said first noted band.
